(57) **CLAIM**

The ornamental design for a pole for string lights, as shown and described.

DESCRIPTION

FIG. 1 is a perspective view of a pole for string lights showing our new design;

FIG. 2 is a bottom view thereof;

FIG. 3 is a top view thereof;

FIG. 4 is a front view thereof;

FIG. 5 is a rear view thereof;

FIG. 6 is a left side view thereof; and,

FIG. 7 is a right side view thereof.

The double S shaped line breaks are indicative of indeterminate length and form no part of the claimed design.
